Primary Examiner—Terry A Wallace*(74) Attorney, Agent, or Firm*—Gregory S. Bollis(57) **CLAIM**

I claim the ornamental design for a dispensing closure, as shown and described.

DESCRIPTION

FIG. 1 is a perspective view of a dispensing closure showing my new design;

FIG. 2 is a bottom plan view thereof;

FIG. 3 is a top plan view thereof;

FIG. 4 is a side view thereof; and,

FIG. 5 is another side view thereof.
